UNITED STATES PATENT OFFICE.

BENJAMIN F. FARRAR, OF SAN FRANCISCO, CALIFORNIA.

FOLDING BED.

SPECIFICATION forming part of Letters Patent No. 327,077, dated September 29, 1885.

Application filed June 9, 1884. (No model.)

To all whom it may concern.

Be it known that I, BENJAMIN F. FARRAR, of the city and county of San Francisco and State of California, have invented an Improvement in Folding Beds; and I hereby declare the following to be a full, clear, and exact description thereof.

My invention consists in the particular arrangement and construction of guide-strips by which the legs and leg-frames of the bed are kept in an upright position, and in the stops by which these guide-strips are limited in their movement to enable the legs of the frame to come to their proper position.

It consists, further, in certain details of construction, hereinafter described, pertaining to the limitation of the mattress and the general cabinet structure of the bed.

The object of my invention is to provide a simple, comfortable, and easily-operated bed adapted when not in use to be folded up out of the way.

Referring to the accompanying drawings, Figure 1 is a perspective view showing the bed open. Fig. 2 is a longitudinal section of same. Fig. 3 is a section on line $x-x$, Fig. 2. Fig. 4 is a vertical section showing the bed closed. Fig. 5 is a perspective view of the folded bed to show its cabinet-like exterior.

A are angular three-sided frames forming the carriers or legs and provided with suitable casters, a . To the top of these are hinged by hinges b the frames B, forming the beds of the mattress. These are hinged together at their meeting edges by hinges b' , adapting them to fold together in a vertical position and to open out to one continuous plane in a horizontal position. When the former movement takes place, the leg-frames A approach each other, and when the latter movement is effected they separate their limit. The hinges b' between the bed-frames B are at the top of their meeting edges, and therefore the frames in folding are depressed at their centers and move down between the approaching leg-frames until their lower portions are inclosed by them, Figs. 1, 4.

Upon unfolding the inner portions of the bed-frames rise from between the separating leg-frames until a horizontal is reached. This manner of folding the bed-frames enables me to dispose of a portion of the frames between

the leg-frames, and to make the bottoms of the upper portions serve as the exteriors of the casing or cabinet of the bed when folded, 55 the mattress of the bed being thereby completely concealed. The operation of folding and opening is also rendered easy, as a sufficiently great leverage is obtained on the outer ends of the bed-frames to easily tip them. 60

The width of the frames B is less than the length of the leg-frames A, so that the sides of the former play inside of the ends of the latter. The object of this I shall presently show. 65

In the movement of the frames B, they being hinged on the edges of the leg-frames, these latter have a tendency to tip or trip on their casters, instead of remaining and moving steady and perpendicular on the floor. To remedy 70 this, and to guide the leg-frames, I have the following: From the ends of one of the leg-frames extend, in a horizontal position in the direction of the other leg-frame the guide-strips D, one near the top and the other lower down. From 75 each end of the other leg-frame extends a guide-strip, E, in a horizontal position, and occupying a plane about midway between the opposing strips D. F is a supplementary leg, having a caster, and G is a similar leg. Secured to the leg F are the guide-strips f, extending horizontally about an equal distance on each side of the leg. The upper one of the strips f is just under the strip D, and fits its lower edge by means of a suitable tongue 80 in one and groove in the other, as shown. The lower strip f is just above the lower strip D, and slides upon it by means of a tongue and groove, as indicated. Secured to the leg G are the guide-strips g, which respectively 85 fit and slide upon and under the guide-strip E by a tongue-and-groove connection. The strips g also fit, respectively, under and upon the strips f, and slide by means of a tongue and groove. These various strips guide and 90 stiffen the legs in their movement, and prevent them from tripping, making them run true and perpendicular, and it is obvious that 95 by a suitable series of such guide-strips I may provide any number of supplementary 100 legs. The legs F G, when the bed is folded, lie between the leg-frames A, and when the bed is opened they support its center.

It is necessary in the movements of the

guide-strips of the leg-frames and legs to provide certain stops by which they are prevented from separating entirely, and by which they are enabled to govern and direct each other's movements to cause their legs to come to their proper places upon folding or opening the bed. Accordingly I have the following arrangement of stops, Fig. 2: Upon the pair of guides *f*, near their outer ends, are stops *f'*, in the shape of projecting screws, which are adapted to come in contact with a stop, *d*, on the guides *D*, and consisting of a tie-strap set far enough out from the face of the guides to permit the stops hereinafter described to slide by without touching, Fig. 3. Upon the outer ends of the pair of guides *g* of leg *G* is stop *g'*, consisting of a tie-strap let in flush with the inner surface of the guides to enable it to slip by the stops hereinafter mentioned. This stop is adapted to come in contact with a shoulder, *e*, on guide-strip *E*. Upon the inner ends of the pair of guides *f* is a stop-strap, *f''*, and upon the inner ends of the pair of guides *g* is a stop-strap, *g''*, adapted to come in contact with stop *f''*. By this arrangement of stops the guides are limited and governed in their movements, and yet pass by each other without interference. The stops also serve to brace the pairs of guide-strips.

H is the mattress, and *I* is an ordinary woven spring fabric or foundation-sheet on which it rests. Under this *I* may or may not place the usual springs, *J*; or *I* may dispense with the spring-foundation *I*, as either this or the springs *J* will answer, as far as the formation of a spring-bed is concerned. The mattress lies within the frames *B*, and is integral, extending nearly the united length of the frames. It is my object to make the mattress lie down in and between the frames when the bed is folded, and to cause it to rise above their edges when opened out. Accordingly I have the following means: Near the head and foot of the frames *B*, and between their sides, are cross-bars *K*, having a length less than the width of the frames, so that they may play up and down therein without friction. These bars are supported on and held by the free ends of arms *L*, the lower or inner ends of which find fulcrum-bearings against blocks *l* or other suitable pivot-bearing secured to the inner surfaces of the frames *B* near their lower edges. These bearings can be made movable for the purpose of separating the cross-bars. To these cross-bars the woven spring fabric *I* is secured, and upon them the ends of the mattress are secured by the straps of ticking *M*. These bars are not directly at the head and foot of the bed, a space being left between them and the head and foot boards; and it will be observed that the mattress and spring fabric *I* are shorter than the distance between the cross-bars when the bed is opened, except when said bars are raised on their pivoted arms to the level of the sides of the frames *B*, Fig. 2. This effects the following result:

When the frames *B* are folded into a vertical position, the tension or stretch on the mattress being relieved, the cross-bars *K* fall down within the frames, and the mattress is completely inclosed by them, Fig. 4. As they open out to a horizontal plane the mattress, in endeavoring to follow them, but being too short to do so completely, can only assume a horizontal position by pulling on the cross-bars, which, being held by the pivoted arms, cannot move together, but must rise, describing a short arc on the fulcrum of their arms, and they thus carry the mattress above the sides of the frame, as shown in Fig. 2.

Now, it is necessary, in order to keep the mattress taut, that the cross-bars *K* should resist the further pulling of the mattress and to have a limit to their upward movement. This limit should be at points between which the mattress is the most stretched. Blocks or pins, against which the cross-bars come in contact, or other similar devices, could be employed for this purpose; but I have found them inconvenient, as being liable to catch the clothing of the bed, and I have therefore adopted the flexible strap *N*, secured to the cross-bars and to the bottom of frames *B*, Figs. 2 and 3. If after use the mattress should become lengthened by stretching, all that is necessary is to set the fulcrum-blocks *l* nearer the outer ends of the frames, thus separating or increasing the distance between the cross-bars, whereby they may hold the mattress stretched.

As the length of the frames *B* is lessened by the depression of their hinged center the tension on the mattress is relieved, and the cross-bars, being no longer supported thereby, drop down into the frames, as mentioned, and when the frames meet the mattress lies snugly between them.

The remaining feature of my bed relates to its frame-work and its appearance when closed as a result of the construction.

The leg-frames *A* and the supplementary legs *F G* constitute the base of a cabinet-like structure which the bed assumes, as shown in Fig. 5, when in a folded position. The exterior surfaces of these parts are therefore suitably carved and provided with moldings to complete this appearance, and the fact that the bed-frames *B* are narrower than the leg-frames are long gives the effect on the ends of the upper portion of the cabinet by the formation of a shoulder. Upon this shoulder is a facing-strip, *O*, which is secured to but one of the leg-frames, thus allowing the other, as well as the supplementary legs, to play under it. In this facing is a bolt, *P*, operated by a thumb-piece, *p*, and adapted to shoot within a socket in one of the bed-frames when opened to a horizontal position, in order to hold the bed and prevent it from collapsing when pressure is brought on its center alone, Fig. 3.

A spring-latch or other suitable catch may be used instead of the bolt.

The bottom of one of the bed-frames, which

becomes, when folded, the exterior and front of the cabinet, is suitably carved and provided with moldings, and the head-board Q, which is secured to this frame, has its outer surface suitably prepared and given a rail, &c., to give it the appearance of the top of a cabinet.

Having thus described my invention, what I claim as new, and desire to secure by Letters Patent, is—

1. In a folding bed in which a sectional hinged mattress-frame is mounted upon carriers, the rolling leg frames or carriers A and the supplementary rolling legs F G, in combination with the horizontal guide-strips D E f 15 g, secured to said leg-frames and legs and sliding upon and between one another, substantially as herein described.

2. In a folding bed, the rolling leg frames or carriers A, upon which the sections of the bed-frame are hinged, and the supplementary rolling legs F G, in combination with the horizontal guide-strips D E f g, secured to said leg-frames and legs and sliding upon and between one another as described, and the series of 25 stops by which the movements of the guide-strips are limited and governed, consisting of the stops f' f² on the guides f, the stops g' g² on the guides g, stop d on guides D, and stop e on guide E, all arranged and operated substantially as herein described.

3. The rolling leg-frame A, provided with the horizontal guide-strips D and E, and the bed-frames B, to which the leg-frames are hinged, in combination with a bolt, P, on one

of the leg-frames, adapted to engage with one 35 of the bed-frames to prevent their folding, as herein described.

4. The combination, with the rolling leg-frame A and the rolling supplemental legs F and G, each provided with horizontal guide-strips and forming, when closed, the base of 40 the bed casing or cabinet, of the bed-frames B, the mattress H, and the arms L, cross-bars K, the blocks l, and the straps securing the cross-bars to the frames, all combined and arranged 45 to operate as herein described.

5. In a folding bed, the hinged bed-frames B, in combination with the mattress H, the loosely-playing cross-bars K within said frame, and to which the ends of the mattress 50 are secured, the arms L, secured by one end to the cross-bars and pivoted by the other to bed-frames, and the flexible straps N, secured to the cross-bars and to the bed-frames, whereby the upward movement of the cross-bars is 55 limited, substantially as herein described.

6. In a folding bed, the hinged bed-frames B, in combination with the mattress H, the cross-bars K, the straps M, securing the mattress to the cross-bars, the straps N, securing 60 the cross-bars to the frames, and the arms L, substantially as herein described.

In witness whereof I have hereunto set my hand.
